SIMPLIFIED FEED UNIT FOR SERIALLY CONNECTED WIRING UNITS

Joseph F. O'Brien, Lebanon, and Earl S. Boynton,
East Orange, N. J., assignors to John B. Pierce
Foundation, New York, N. Y., a corporation of
New York

Application November 25, 1944, Serial No. 565,148

2 Claims. (Cl. 173—334.1)

1

The present invention relates to electric wiring systems employing serially-connected wiring units or ducts, and more particularly to feed or supply units for such systems.

An object of the present invention is to provide a unit of the character described of simple construction, employing a minimum of parts, easy to assemble, and withal having high structural and electrical integrity.

A feature of the present invention includes the provision of a feed unit encased in molded insulative material having binding posts which do not require supplemental means for retaining the same in place, nor require molding in such posts as metal inserts.

An object of the present invention is to provide a feed unit in which the conductors and casing parts cooperate to hold the binding posts in place.

Pursuant to the present invention, the conductors pass through the feed unit and may be conventional electrical conductors, that is, of relatively less surface area than comparable bus bars; however, the present invention does not preclude the use of bus bar types of conductors, if so desired. For general purposes conductors of usual cross-section employed in conventional wiring systems adequately subserve the requirements of current carrying capacity, pursuant to the present invention.

While the present invention has been exemplified herein by feed units of the type providing connection to the supply line rearwardly of the unit, it is apparent that the invention is also applicable to feed units wherein the supply line may be connected at either side or at the end of the unit.

Further features and objects of the invention will be more fully understood from the following detailed description of the accompanying drawings, in which:

Fig. 1 is a top plan view of the closure base plate;

Fig. 2 is a similar view of the base plate showing the binding posts and conductors in place;

Fig. 3 is a bottom plan view of the main casing member;

Fig. 4 is a top plan view of the main casing member placed in operative position over the closure base plate, the electrical conductors being omitted for clarity of illustration;

Fig. 5 is a top plan view of the completed unit;

Fig. 6 is an end elevation looking in the direction 6—6 of Fig. 5;

Fig. 7 is an end elevation looking in the direction 7—7 of Fig. 5; and

2

Fig. 8 is a detail sectional view on line 8—8 of Fig. 4.

Referring to the drawings, it is observed that the illustrated unit comprises a closure base plate 10, a main casing member 11, and a removable cover plate 12.

As shown, the main casing member 11 is closed at its longitudinal sides and is provided with a floor, as particularly indicated in Fig. 8. The top of the casing member is substantially closed except for a longitudinally extending opening which is provided with a removable cover plate 12. The base plate 10 is shown provided with longitudinal grooves 10a, 10a, in which are disposed the electrical conductors 13, 13. The grooves 10a, 10a, preferably merge with the grooves 10b, 10b, which are of preferably greater depth and width as compared with said grooves 10a, whereby to accommodate a part of the lugs 14, 14, which are respectively attached to the conductors 13, 13.

The base plate 10 is also provided with recesses 10c, 10c, which are arranged to receive metal members or binding posts 15, 15, which are each bifurcated at one end for a desirable extent, and provided with threading on the inner walls of their bifurcated portions.

The base plate is also provided with an opening 10d through which the leads of the supply cable 30 may be passed for connection to the binding posts 15, 15. Arranged to be disposed over the base plate is a main casing member 11. On the bottom surface of the floor of the main casing member, see Fig. 3, are longitudinal grooves 11a, 11a, 35 which complement with the grooves 10a, 10a, of the base plate to form conduits for the conductors 13, 13, respectively. As in the base plate, the longitudinal grooves 11a, 11a, of the casing member merge into recesses 11b, 11b, of relatively 40 greater depth and width, whereby to accommodate the remainder of the lugs 14, 14.

The casing member is also provided with holes 11c, 11c, through which the binding posts 15, 15, project for access from the exterior of the unit. 45 The floor of the casing member is also provided with holes 11d, 11d, preferably separated by a transverse wall 11e, to afford entry of the leads of the supply cable and preferably thus held spaced apart from one another.

50 Figs. 2, 4 and 8 illustrate the conductors 13, 13, passing respectively through the slots 15a of the bifurcations of the binding posts 15, 15, and connection made with the supply lines, indicated at 20, 20, to the binding posts by means of screws 55 16, 16, which respectively not only clampingly

engage the supply wires 20, 20, and the binding posts, but which also make pressure contact with the respective conductors 18, 18.

In order to secure the base plate to the main casing member, holes 10₁, 10₂, are provided in the base plate, said holes being aligned with holes 11₁, 11₂, in the bosses 11₁, 11₂, in the floor of the casing member, for the reception of suitable screws or the like.

For securement of the top cover plate 12 to the casing member 11, holes 12_a, 12_a, are provided in said cover plate 12 which are aligned with holes 11₃, 11₃, in bosses 11₃, 11₃, of the casing member, and screws passing through the such registered holes respectively.

The feed unit as above described is typical of a feed unit of general character. The feed unit as specifically illustrated is particularly adapted for seriatim connection in an electrical conduit system, for which purpose the opposite ends of the feed unit are respectively of male and female formations, the male end being indicated at 17 and the female end at 18. For such seriatim connection, the lugs 14, 14, are hollow-formed, see 14_a, 14_a, see Figs. 2 and 5, to provide sockets thereat for frictional reception of the end portions 13_a, 13_a, see Figs. 2 and 6, of the respective conductors 13, 13, of the thereto connected adjacent unit of such seriatim conduit system.

For mechanical securement of the overlapping end portions of adjacent units, the male end 17 is provided with a perforation 17_a, and the female end 18 with a therewith registering perforation 18_a, through which may be passed a screw 19. Such manner of securement by screws 19 to the respective end portions of adjacent units may serve also for attaching the conduit units to any suitable support, as to the wall of a building, or other suitable base or the like.

We claim:

1. A back connection electrical feed unit comprising a base having an opening therein for the passage therethrough of the leads of a power source, and further having longitudinal grooves for the reception freely therein of electrical conductors, a body member having a floor provided with openings for the passage therethrough respectively of the leads of a power source, and longitudinal grooves in the bottom of said floor complementing with said longitudinal grooves of said base in the reception freely of the electrical con-

ductors, binding posts mounted in said base respectively in alignment with said longitudinal grooves of said base and projecting through said floor, electrical conductors freely disposed in said complementary longitudinal grooves and freely engaging said binding posts, means for connecting the leads of such power source to said binding posts, and fastening means passing through the floor of said body member and said base for jointly securing said electrical conductors in position in said complementary longitudinal grooves and the feed unit as an entirety at a suitable support.

2. A back connection electrical feed unit comprising a base having an opening therein for the passage therethrough of leads of a power source and further having longitudinal grooves, a body member having a floor provided with openings for the passage therethrough respectively of the leads of such power source and further having longitudinal grooves in the bottom of said floor complementary with said longitudinal grooves of said base, binding posts mounted in said base respectively in alignment with said longitudinal grooves of said base and projecting through said floor, said binding posts having slots therein, electrical conductors freely disposed in said complementary longitudinal grooves, respectively and engaged in said slots of said binding posts, means for connecting the leads of such power source to said binding posts, and fastening means passing through the floor of said body member and said base for jointly securing said electrical conductors in position in said complementary longitudinal grooves and the feed unit as an entirety to a suitable support.
